UNITED STATES PATENT OFFICE

MAURICE ALLAND, OF ATLANTIC CITY, NEW JERSEY

GARMENT SUPPORTER

Application filed October 7, 1929. Serial No. 397,873.

The object of the invention is to provide improvements in garment supporters, but more particularly in that type which is designed for supporting one's trousers directly by and from one's shirt.

Another object is to provide in such a device means to permit attachment to and detachment from one's shirt with rapidity and at any desired locality, whether adjacent to a side seam as is preferred, or forwardly or rearwardly thereof.

A further object is to provide in such a device means to permit attachment to and detachment from the belt of one's trousers with equal or even greater rapidity and at any desired locality, longitudinally of such belt about the circumference of one's body.

Still another object is to provide an efficient form of elastic connection between said shirt and belt-attaching means, to permit free movement of the wearer in bending forwardly, rearwardly, or sidewise, without placing an otherwise unyielding strain either upon the belt or upon the relatively weaker shirt.

And a still further object is to provide means for detachable connection to one's trousers, whereby the device may be readily connected thereto or disconnected therefrom when a belt is not in use.

With these and other objects in mind, the present invention comprises further details of construction and operation which will be clearly brought out in the following description when read in conjunction with the accompanying drawings, in which Fig. 1 is an elevation of the device in its preferred embodiment as applied to a shirt-trouser-belt combination; Fig. 2 is a vertical section of the same on the line 2—2 of Fig. 1; Fig. 3 is a perspective view of the parts of the device per se; Fig. 4 is a perspective view of a portion of the upper marginal area of trousers equipped with means for connecting the supporter thereto when a belt is not used; and Fig. 5 is a horizontal section of the same taken longitudinally through said means.

Referring to Figs. 1, 2 and 3 of the drawings, a shirt or other upper garment 10 having a seam 11 is illustrated as representing

any one of several garments which are worn upon the upper part of the body and are supported wholly or in part from the wearer's shoulders. A pair of trousers 12 on the other hand represents any one of several garments which are worn upon the lower part of the body, and which are usually supported indirectly by the shoulders through the medium of the shirt or similar garment above mentioned, said trousers in this instance being provided with any well-known form of belt 13, but which as a supporting means has its limitations and is by no means positive in preventing the trousers from slipping downwardly, or the shirt from becoming loosened and moving relatively upwardly from beneath the trousers.

The garment supporter per se comprises two principal elements as shown in Fig. 3. The shirt-attaching element comprises a shank 14, carrying an enlarged head 15 upon one end and upon its opposite end a relatively smaller head preferably provided with an annular rubber ring 16. The other element of said supporter comprises a member 17, having an enlarged aperture 18, and a longitudinally extending projection 19, having an offset 20 to said aperture. The opposite end portion of said last-named element is provided with a transversely extending aperture 21, normally inclosed by two arms 22 which are integral with the opposite sides of said element and after extending freely therefrom for a short distance, proceed in alignment towards each other as shown in dotted lines in Fig. 1.

A terminal element 23, having a hooked extension 24, is also provided with arms 25, similar to the arms 22 and inclosing a transversely extending aperture 26. By originally and temporarily deflecting the arms of the respective pairs out of alignment with each other, it is obviously possible to insert in said apertures the diametrically opposite portions of the cylindrical wall of a section of tubing 27. Such an element as a piece of flexible and transversely elastic tubing it will be noted permits relative separation of the elements 17 and 23, while the tubing flattens in one direction transversely before

altering its circumferential measurement, and thereafter permits said elements to further separate as the flattened tubing stretches in its assumed plane and increases its peripheral dimensions.

Thus, in the operation of the device, the headed element 14 is held against the inner surface of one's shirt or the like, and the element 17 pressed thereupon so that the head 16 and adjacent shirt material are forced through the aperture 18, after which they are drawn into the aperture offset 20, thereby detachably but normally firmly securing said element to the shirt, and at any locality thereon but preferably adjacent to the side seam 11. The hooked element 24 is then inserted downwardly between the trousers 12 and belt 13 until it is possible to engage said belt with said hook, as clearly shown in Figs. 1 and 2. Thereafter, it is obvious that while the trousers are free to yield downwardly and angularly with respect to the shirt through the flexibility and elasticity of said tubing as above described, the trousers cannot drop freely from a predetermined, substantially fixed height. The hook 24 can also be disengaged from the belt wherever desired, and can be readily shifted longitudinally of the belt into any one of an infinite number of positions.

However, as in the case of a so-called evening suit when a belt is not worn, the trousers 30 may be provided with a staple having a flattened portion 31 and threaded end portions 32, which are adapted to be run through the material of the trousers and secured in operative position by means of nuts 33, which may possess the shape of buttons or otherwise as may be desired. With this trousers attachment the supporter as a whole operates in the same manner as before described, though it is not laterally adjustable upon and with respect to the trousers, as when a belt is in use.

Having thus described my invention, what I claim and desire to protect by Letters Patent of the United States is:

1. A garment supporter, comprising the combination of a separate button normally positioned upon one side of the material of a garment, with an element normally positioned upon the opposite side of the garment and having an aperture adapted to receive said button and garment material extending thereacross, said aperture having an extension of decreased width to bind such material to said button and thereby prevent said button from shifting its predetermined position with respect to the garment, said element having integral normally aligned fingers, capable of being flexed to receive a tubular member, a supporting element also having integral normally aligned fingers, capable of being flexed to receive a tubular member, and a tubular member extending

around the fingers of said elements, to operatively connect said supporting element to a garment through the medium of said first element and said button.

2. A garment supporter, comprising the combination of a separate button normally positioned upon one side of the material of a garment, with an element normally positioned upon the opposite side of the garment and having an aperture adapted to receive said button and garment material extending thereacross, said aperture having an extension of decreased width to bind such material to said button and thereby prevent said button from shifting its predetermined position with respect to the garment, said element having integral normally aligned fingers, capable of being flexed to receive a tubular member, a supporting element also having integral normally aligned fingers, capable of being flexed to receive a tubular member, and an elastic tubular member extending around the fingers of said elements, to operatively connect said supporting element to a garment through the medium of said first element and said button, and permit said elements to yield with respect to each other.

In testimony whereof I have affixed my signature.

MAURICE ALLAND.
